UNITED STATES PATENT OFFICE.

ARTHUR J. SHAW, OF SPOKANE, WASHINGTON.

CATTLE GUARD.

Application filed January 31, 1927. Serial No. 164,879.

My present invention relates to improvements in cattle guards for use along public and private highway crossings to prevent cattle and other stock from trespassing upon the right of way of a railway. The cattle guard is of that type utilizing rotary, barbed, or studded, bars that are removably journaled, transversely of the railroad, in guard rails extending parallel with the track rails.

As herein illustrated and described the rotary bars are located between the track rails and at the track side, or along the outer sides of the track, and they are arranged in sections, but it will be understood that other arrangements may be made if desired. The rotary, barbed bars, however are fashioned in quantities of similar size and shape and they are capable of use at different places with relation to the track rails.

The cattle guard is composed essentially of but two elements, the guard rails and the rotary bars, and these parts may be cast from molten scrap metal, thus reducing their cost of production, rendering them easy to crush under the weight of a moving train without danger of derailing the train, and yet providing the required strength to sustain the weight of trespassing stock.

The removable rotary bars are journaled in pairs of parallel rail bars or guard rails in such manner as to permit their quick and easy removal when necessary to tamp or otherwise repair the road bed, or for the purpose of clearing the track or tracks to permit cattle to be driven across the track. The stationary guard rails are affixed, as by lag screws, to the cross ties in such manner as to be readily removable if and when it is necessary to repair or replace the underlying ties. Due to the minimum number of parts used and to the simplicity in construction and operation of the cattle guard of my invention, it has proven highly successful and satisfactory in actual use on railroads, and is now being used under these successful and satisfactory conditions.

My invention consists in certain novel combinations and arrangements of parts involving the stationary guard rails and the rotary studded, bars or spindles, as will hereinafter be more fully set forth and claimed.

In the accompanying drawings I have illustrated one complete example of the physical embodiment of my invention wherein the parts are combined and arranged ac-

cording to the best mode I have thus far devised for the practical application of the principles of my invention.

Figure 1 is a plan view, partly broken away, showing the cattle guard applied between the rails and at the trackside of a railroad.

Figure 2 is a sectional view at line 2—2 of Figure 1.

Figure 3 is a fragmentary, perspective view of one of the guard rails.

Figure 4 is a fragmentary, perspective view of the center guard rail, located between the track rails.

Figure 5 is a vertical sectional view through the central guard rail.

Figure 6 is a view of one of the rotary, studded, bars.

In order that the general assembly and arrangement of parts may readily be understood I have indicated in Figures 1 and 2 the track rails R. R. and the cross ties T, T of a single track railroad to which the cattle guard is applied.

The guard rails are designated as 1, 2, 3, 4, 5, 6, and 7 and they are preferably cast rails, of inverted T-shape and provided with an upright web as 8 which is of sufficient height, in the case of the center rail 4, to support and permit a fallen brake beam to ride over its top edge without injury to the cattle guard.

These guard rails as shown are disposed longitudinally of the track rails and are of suitable length for the purpose for which they are intended. At equidistant points throughout the length of the guard rails they are provided with enlargements or lugs some of which are single lugs 9 and others double lugs 10, the single lugs being located at one side of the web 8, and the double lugs being fashioned at both sides of the web 8 of the center guard rail 4.

Some of the single lugs 9 (as in rails 2, 3, 5 and 6) have round sockets 11 opening from one side of the rail and some of the lugs 9, as rails 1 and 7 (the outer guard rails at the outside of the track) are provided with, vertically arranged, elliptical sockets 12 and the side walls of these elliptical sockets are provided with open slots 13.

The double lugs of the center guard rail are also provided with these sockets 12 and slots 13, at opposite sides of the center web 8, and the slots 13 at opposite sides of the web opening opposite directions.

The guard rails are arranged in pairs, spaced apart as indicated, and secured, as by lag screws to the cross ties, with a series of round sockets 11 facing a series of elliptical sockets 12, and the elliptical sockets at the opposite sides of the center guard rail 4 face series of round sockets in the lugs of the guard rails 3 and 5 at the inner sides of the track rails R and R.

- 10 Between guard rails of a pair a series of rotary, barbed or spiked bars 14 are journaled with their end journals 15 in the respective sockets, and the studs 16 on these bars or spindles are arranged in spiral formation, three spirally arranged series of studs being illustrated in Figure 6.

By the spiral arrangement herein referred to, adjacent groups of spines are disposed angularly so that the spines are regularly 20 staggered on the bar, the spines of adjacent groups being displaced by an angle of 60 degrees. Consequently when a cow's foot is set upon a spine of one group so as to turn that spine downward, before that spine has moved 25 more than 60 degrees the adjacent spine of a group on one side or the other, will strike the side of the cow's foot, tending to push the foot sidewise, causing the cow to lift its foot from the descending spine in order to obtain 30 a firmer foothold. Thus the cow will move its foot before it descends low enough to pass beneath a pair of spines on adjacent bars, in which position the foot would be irreleasably held resulting in injury to the cow.

35 One end 15 is slipped into a socket 11 and the other end of the rotary bar is passed laterally through the slot 13 and deposited in the bottom of the elliptical socket 12 of the opposite guard rail of a pair, and the rotary 40 bars are spaced apart and arranged in parallelism as indicated in Figure 1. They may readily be removed when desired, by slipping one journal through its slot 13 and then pulling the other journal from its socket 11.

45 The parallel rotary bars are spaced apart a sufficient distance to prevent the hoof of

an animal from resting on two bars to prevent the animal walking on the guard, but they are sufficiently close to prevent the animal's foot from passing through the space 50 between them. When the foot or hoof is placed between a pair of bars, the studs on the respective bars are turned inwardly toward the hoof to pinch it sufficiently to cause the animal to withdraw the hoof and back 55 off the guard.

Having thus fully described my invention, what I claim as new and desire to secure by Letters Patent is—

1. A cattle guard comprising a center 60 guard rail having spaced double-lugs and elliptical sockets in the opposite faces of said lugs having open slots, guard rails along the inner sides of the track rails having spaced lugs with round sockets therein, and studded, 65 rotary guard bars having journal ends in said sockets.

2. A rotary cattle bar for cattle guards comprising an integral casting made from scrap iron of such character as to be breakable under the impact of a blow from a wheel 70 of rolling stock, formed with trunnions at its opposite ends, and intermediately formed with laterally extending blunt spines arranged around the axis of said bar.

3. A cattle bar for cattle guards comprising a rotatable spindle provided with blunt spines projecting radially thereof, arranged in groups of three, the spines of each group being equally circumferentially displaced, 75 the groups being disposed in parallel planes perpendicular to the axis of said spindle, and intersecting said axis at distance intervals of such length as to cause a cow's foot when set upon a spine of one group to be in the path 80 of movement of spines in an adjacent group, the spines of adjacent groups being arranged at a relative angular displacement of approximately half the angle between the spines of a group.

In testimony whereof I affix my signature,

ARTHUR J. SHAW.
